United States Patent Office

Des. 219,296
Patented Nov. 24, 1970

219,296

POLISHING MACHINE OR SIMILAR ARTICLE

John L. Weber, Spencerport, N.Y., assignor to Alliance
Tool & Die Corp., Rochester, N.Y., a corporation of
New York

Filed Aug. 4, 1969, Ser. No. 18,520

Term of patent 14 years

Int. Cl. D15—05

U.S. Cl. D37—1

FIG. 1

FIG. 2

FIG. 3

FIG. 4

FIG. 1 is a perspective view of a polishing machine or similar article, taken from the front left corner and showing the front and left sides;

FIG. 2 is a right side view;

FIG. 3 is a rear view; and

FIG. 4 is a top view, the bottom being plane and unornamented.

I claim:

The ornamental design for a polishing machine or similar article, as shown and described.
